UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPOGRAPHICAL COMPOSING-MACHINE.

1,109,845.

Specification of Letters Patent.

Patented Sept. 8, 1914.

Application filed April 22, 1912. Serial No. 692,235.

To all whom it may concern:

Be it known that I, DAVID SHERWOOD KENNEDY, a citizen of the United States, and a resident of Brooklyn, county of Kings, and 5 State of New York, have invented a new and useful Improvement in Typographical Composing-Machines, of which the following is a specification.

My invention relates to typographical 10 composing machines, such as linotype machines of the general organization represented in U. S. Letters Patent to O. Mergenthaler, No. 436,532, wherein circulating matrices are released from a magazine or 15 magazines in the order in which their characters are to appear in print, and then assembled in line together with expanding spacers, the composed line transferred to the 20 face of a mold, the mold filled with molten metal to form a slug or linotype against the matrices which produce the type characters thereon, and the matrices thereafter elevated and returned through a distributing mechanism to the magazine or magazines from 25 which they started.

More particularly, it relates to the form of machine disclosed in the application for Letters Patent of John R. Rogers, Serial No. 624,426, filed May 1, 1911, wherein is employed a series of magazines in combination with means for shifting them and for locking any selected one thereof in operative position; and wherein also are provided devices to ascertain the presence or absence of 30 matrices in the distributing mechanism, and to prevent the shifting of the magazines while any matrices of the magazine in position remain undistributed. Specifically, 35 these means comprise a manually operable feeler, which enters the distributing mechanism freely when the latter is empty, but which is prevented from so doing when matrices are present therein. In the said Rogers application, this feeler actually contacts 40 with the undistributed type or matrices, and it follows that the too forcible or careless repetition of this action tends to injure the matrices, and particularly the tooth-combinations thereon, and in addition it sometimes happens, when the pressure on the 45 matrices is relieved, that they drop into the wrong channels. These undesirable consequences result largely from the continued 50 operation of the distributing mechanism, and particularly the conveying screws there-

of, after the feeler is brought into contact with the matrices. In order to obviate these difficulties, I have provided additional means whereby the distributing mechanism is arrested, when the feeler is projected into it and there contacts with the undistributed matrices. To this end I prefer specifically to make the contact bar or feeler longitudinally movable in relation to the distributing mechanism and its screws, and 55 I rely on this relative movement to effect the action of the stop mechanism.

In the accompanying drawings, I have shown my invention in preferred form and by way of example, and as applied to a linotype machine, but obviously it may be varied in many ways, or used in connection with other forms of typographical machines, such as typesetters, typecasters, or the like, without departure from its spirit; and generally speaking, I desire it to be understood that I do not limit myself to any specific form or embodiment except in so far as such limitations are specified in the claims.

Referring to the drawings: Figure 1 is a 80 side view of a portion of a linotype machine, having my invention applied thereto; Fig. 2 is a rear view, on an enlarged scale, of a portion of the distributing mechanism; Fig. 3 is a section, taken substantially on the line 85 2-3 in Fig. 2; and Fig. 4 is a detached plan, illustrating the mode of suspension of the feeler.

Referring to Fig. 1, the magazines A¹, A², A³, are mounted in the shift frame A, which 90 may be moved to bring any selected magazine into operative position, by the manipulation of the wheel C and through suitable connections C¹ therefrom to the frame. The selected magazine is registered and locked 95 in operative position by the engagement of the longitudinally movable bar B in a properly located notch A¹⁰ formed in the frame A, the various necessary movements of the locking bar B being imparted thereto 100 through suitable connections B¹ from the operating handle B². The distributing mechanism comprises the usual rail F and screws G; and the blade or feeler E is arranged to be projected into the distributing 105 mechanism between the screws by the pivoted lever D, which in turn is controlled by the movements of the locking bar B. The parts so far described constitute specifically no part of my present invention, and are or 110

may be substantially similar to those disclosed in the previously mentioned Rogers application.

Turning now to my improved devices, it will be noted that the blade or feeler E is pivotally suspended from the rod E¹, and that its inner edge, which contacts with the matrices X, is preferably serrated or provided with teeth E² in such manner that when the bar is brought into contact with the matrices, which are being advanced along the rail F by the screws G, its teeth are engaged by the moving matrices, which therefore tend also to move the blade therewith. Referring to Fig. 4, it will be noted that the blade E is capable of longitudinal movement on the rod E¹ and that it is held in normal position by the spring E³. When the matrices engage the teeth E² thereof in the manner previously described, the bar is moved against the force of the spring E³, and it is this longitudinal movement on which I rely to effect the arrest of the distributing mechanism.

The particular stopping means constitute no part of my present invention and may be of any well known or approved form. In Figs. 2, 3 and 4, the screws G are driven in the customary manner by devices which comprise the friction clutch members P and Q, the former being laterally movable to make and break the actuating connection. In proximity to the end of the blade or feeler E is mounted the arm or catch J, connected to the usual movable stop bar H, in such position that the longitudinal movement of the blade E disengages the arm J from the detent K. The detent K is mounted upon a rock shaft L, which also carries an arm M, formed with a pin N adapted to engage the lateral cam face O on the movable clutch member P. The spring L¹ tends to engage the pin N with the cam O, but this action is resisted and controlled in normal operation by the contact of the detent K with the arm J.

The operation of the parts will now be understood. When all of the matrices have been distributed and consequently none remain on the rail F, the blade E may be freely projected between the screws G, which operation is illustrated by dotted lines in Fig. 3. This action results in the unlocking of the magazines to permit their shifting, as disclosed in the said Rogers application. If, however, matrices X are still present in the distributor, the blade E is arrested thereby (see full lines in Fig. 3), and the teeth E² are brought into engagement therewith. The screws G continue to move the matrices along the rail, and due to their engagement with the teeth E², the bar E is shifted longitudinally, thereby releasing the arm J from the detent K, and permitting the spring L¹ to turn the rock shaft

L and arm M, and to throw the pin N into the path of the cam O. Due to this latter engagement, the further rotation of the clutch member P shifts it laterally so as to open the friction clutch and thus to arrest the rotation of the screws.

The parts are so arranged and adjusted that the stoppage of the distributing mechanism occurs almost instantly after the blade E contacts with the matrices, and consequently the resultant friction and injury to the matrices and parts, the liability to improper distribution, etc., are reduced to a minimum. It therefore follows that the presence of matrices in the distributing mechanism not only prevents the unlocking and shifting of the magazines, but also instantly arrests the distributing mechanism in the event of an attempt to unlock them.

In order to start the operation of the distributing mechanism again, after it has been thus arrested, it is necessary to re-set the parts, which may be done simply by rocking the shaft L against the force of the spring L¹, at which time the detent K contacts with an inclined surface on the arm J, thus moving the arm and the bar H out of the way, and permitting the detent K to resume its normal or set position behind the arm J.

As previously stated, I have shown my improvements in preferred form and by way of example, but obviously many variations and alterations therein, as well as in their mode of application, will suggest themselves to those skilled in the art and still be comprised within their scope.

Having thus described my invention, its construction and mode of operation, what I claim and desire to secure by Letters Patent of the United States, is as follows:

1. In a typographical machine, the combination of distributing mechanism, means movable into engagement with the type or matrices in normal position therein, and means dependent upon such engagement for arresting the distributing mechanism.

2. In a typographical machine, the combination of distributing mechanism, means operable at will to contact with type or matrices in normal position therein, and devices connected thereto to arrest the distributing mechanism and controlled by such contact.

3. In a typographical machine, the combination of distributing mechanism, means to determine the presence or absence of type or matrices in normal position therein, and connections from said means to arrest the distributing mechanism.

4. In a typographical composing machine, the combination of distributing mechanism, a feeler capable of projection into the distributing mechanism to determine the presence or absence of type or matrices in normal position therein, and connections

from said feeler to arrest the distributing mechanism.

5. In a typographical composing machine, the combination of distributing mechanism, a feeler capable of projection into the distributing mechanism to determine the presence or absence of type or matrices in normal position therein, and also capable of a further relative movement with reference to the distributing mechanism, and connections controlled by its said relative movement to arrest the distributing mechanism.

6. In a typographical machine, the combination of distributing mechanism, a feeler capable of projection into the distributing mechanism to contact with type or matrices in normal position therein, the said feeler being capable also of a further relative movement with reference to the distributing mechanism, and connections controlled by its said relative movement to arrest the distributing mechanism.

7. In a typographical machine, the combination of distributing mechanism, a feeler capable of projection into the distributing mechanism to determine the presence or absence of type or matrices therein, and also capable of a longitudinal movement with reference thereto, and connections controlled by said longitudinal movement to arrest the distributing mechanism.

8. In a typographical machine, the combination of distributing mechanism, the serrated feeler capable of projection into the distributing mechanism to contact with type or matrices therein, and also capable of a longitudinal movement with reference to the distributing mechanism, and connections controlled by said longitudinal movement to arrest the distributing mechanism.

9. In a typographical composing machine, the combination of distributing mechanism comprising conveying screws, a feeler capable of projection between the screws to contact with type or matrices in engagement therewith, and also capable of a longitudinal movement with reference thereto, and connections controlled by said longitudinal movement to arrest the distributing mechanism.

10. In a typographical machine, the combination of distributing mechanism comprising conveying screws, the serrated feeler capable of projection between the screws to contact with type or matrices in engagement therewith, and also capable of a longitudinal movement with reference to the screws, and connections controlled by said longitudinal movement to arrest the distributing mechanism.

11. In a typographical machine, the combination of a plurality of magazines, means

for shifting the magazines to bring one or another into operative position, movable locking means to hold the magazines in their shifted position, and a distributing mechanism, with a feeler operated by the movement of said locking means to detect the presence of matrices in the distributing mechanism, and devices controlled by such feeler for arresting the distributing mechanism.

12. In a typographical machine, the combination of a plurality of magazines, means for shifting the magazines, and distributing mechanism, with means co-operating with the type of matrices in course of distribution to prevent the shifting of the magazines and devices controlled by said means to arrest the distributing mechanism. 82

13. In a typographical machine, the combination of distributing mechanism, means to determine the presence or absence of type or matrices in normal position therein, and devices controlled thereby to arrest the distributing mechanism. 85

14. In a typographical machine, the combination of a plurality of magazines, means for shifting the magazines, and distributing mechanism, with means co-operating with the distributing mechanism to prevent the shifting of the magazines and to arrest the distributing mechanism only in the event that any type or matrices of the machine in position remain undistributed. 95

15. In a typographical machine, the combination of a plurality of magazines, means for shifting the magazines, and distributing mechanism, with a feeler to determine the presence or absence of type or matrices in the distributing mechanism, and devices controlled by the feeler to prevent the shifting of the magazines and to arrest the distributing mechanism while any type or matrices of the magazine in position remain undistributed. 105

16. In a typographical machine, the combination of a plurality of shiftable magazines, and distributing mechanism, with a manually operable feeler to determine the presence or absence of type or matrices in the distributing mechanism, and devices controlled by the feeler to prevent the shifting of the magazines and to arrest the distributing mechanism while any type or matrices of the magazine in position remain undistributed. 115

In testimony whereof I hereunto set my hand this 17th day of April, 1912, in the presence of two attesting witnesses.

DAVID SHERWOOD KENNEDY.
